PORTABLE TYING DEVICE

Clayton E. Young, St. Joseph, Mich.

Application November 26, 1949, Serial No. 129,639

17 Claims. (Cl. 47—1)

1

This invention relates to a small, light weight, hand-operable tying device, to facilitate the tying of grape and other vines, as well as vegetables, flowers, shrubs, and other vegetation, and, in fact, anything requiring tying in a similar manner to wires or other supports.

The principal object of my invention is to provide:

(1) An improved tying device adapted for applying a tie in the form of a self-closing, inexpensive but durable, plastic C-shaped loop or ringlet-shaped tie, the ends of which, when the tie is caused to embrace the vine and wire, tend of themselves to curl or coil closely inside one another for a tight hold, these ties being supplied in strips with short severable connecting webs therebetween, and

(2) An improved tying device comprising a combination tie magazine, dispenser, and applicator in the form of a light portable hand tool in or on which the ties are fed in the strip form, step by step, to the discharge or dispensing end of this hand tool automatically as the pair of scissors-like holding and operating handles of the tool are closed by hand pressure, once for each tie dispensed, both to advance the strip a step and to cut the endmost tie from the strip immediately after its application to the vine and supporting wire or the like, the handles being both spring-returned thereafter to starting position ready for the next operation.

The one handle operates a feed mechanism, and the other handle operates a shear blade to cut off the tie projecting from the tool. The normally closed ties on the strip are spread open by sliding the strip endwise over the hollow conical-shaped body or frame member of the hand tool from the small end toward the dispensing end, this cone member being open longitudinally on the bottom so as to permit placing the same astride the wire or other support at the point where the vine or other vegetation to be fastened extends crosswise of the support, thus enabling proper positioning of the tie in each instance for good fastening. The split cone member is made of sheet metal for lightness and economy and has integral extensions on opposite sides of the open large end serving as supports for the operating handles and feed mechanism.

The invention is illustrated in the accompanying drawing, in which—

Fig. 1 is an end view of a tool made in accordance with my invention, looking at the dispensing end that is on the right hand side in Figs. 2 and 3; Fig. 2 is a bottom plan view of Fig. 3;

2

Fig. 3 is a side view of the tool showing it in position astride a wire and overlying vine, as at the conclusion of a tying operation, one of the ties thus applied being shown to the right of the tool, and

Fig. 4 is an end view of one of the C-shaped ties.

The same reference numerals are applied to corresponding parts in these two views.

Referring to the drawing, the reference numeral 11 designates one of the strips of plastic ties, made in accordance with my invention, and 12 the longitudinally split, conical-shaped, hollow sheet metal body or frame member of the hand tool of my invention, over the small end of which the plastic strip 11 is adapted to be slipped to spread the C-shaped ties 11' of which the strip is composed. In that way, the ends of the ties are spaced far enough, as appears in Fig. 1, when they reach the large end of frame 12, to enable easily straddling the wire 13 and vine 14, as shown in Figs. 2 and 3. Hence, the open side 15 of the large end of frame 12 can be laid astride the wire 13 and placed adjacent a portion of the vine 14 overlying the wire to be fastened with a tie 11', so that the endmost tie can be slipped over the vine and wire to fasten the two together, the tie 11' thus applied being then cut from the strip 11, at the conclusion of the same operation of the tool in which the tie is dispensed and applied, as will soon appear. The ties 11', immediately upon passing the large end of frame 12, close as the ends curl or coil closely inside one another, as shown in Fig. 4, under the tension inherent in the plastic material, and, therefore, these ties afford a tight enough hold for the purpose intended. Also, it is apparent that the plastic material of the ties is well suited for the present purpose, it being substantially unaffected by moisture and weather and also retaining its resilience indefinitely, and being, therefore, free to expand radially as the growth of the vine may require and, hence, constitute no hindrance or source of harm to the vine.

The ties 11' are connected by short webs 16 to form the strip 11, and the web behind the endmost tie projected beyond the end of frame 12 is arranged to be cut through by a knife blade 17 on handle 18 at the end of the forward feed movement of strip 11. The feed movement is obtained by operation of the other handle 19, the two handles 18 and 19 being pivoted, as at 20, on opposite sides of a lateral extension 21 of the large end of the frame, and the handle 19 being operatively connected with a feed disk 22

which is mounted for oscillation, as at 23, between an ear projection 24 on extension 21, and a lateral extension 25 on the diametrically opposite side of the large end of frame 12 from extension 21. The disk 22 has a radial notch 26 in the periphery thereof into which a lug 27 projecting laterally from the inner end of handle 19 extends so that the disk 22 is arranged to be turned in a counterclockwise direction, as viewed in Fig. 3, by closing or downward movement of the gripped outer end of said handle, whereby pawls 28 pivoted on opposite sides of disk 22 and urged by springs 29 toward engaging in the space between two adjoining ties in strip 11, on opposite sides of the connecting web 16, are moved to the right as viewed in Fig. 3 to feed the strip 11 forward enough for the dispensing of one tie 11', the feed movement being positively limited by engagement of a stop pin 30 on disk 22 on the flat top surface of the horizontal wall 31 that connects the ear 24 with extension 21. A coiled spring 32, connected at one end to frame 12 and at the other end to handle 18, as shown in Fig. 1, resists oscillation of this handle with substantially greater resistance than that with which a V-shaped wire spring 33, anchored at its opposite ends on handles 18 and 19, resists oscillation of handle 19. As a result, when the operator, grasping the tool by these two handles, closes his grasp, the handle 18 at first stands still and handle 19 swings downwardly against action of spring 33 alone to feed the strip 11 forward, and then, when pin 30 limits further movement of handle 19, handle 18 is raised against action of both springs 32 and 33 so as to cut off the extended end of strip 11, and thus leave the dispensed tie 11' on the wire 13, fastening vine 14 thereon, as shown in Fig. 2. Upon release of the handles, or rather release of closing pressure thereon, the springs return the handles to starting position, thereby resetting pawls 28 for the next feed.

In operation, the user purchases strips 11 in quantities sufficient for the work to be done and applies the strips one after another onto frame 12, threading the small end into the closed coils formed by the ties 11' in each strip, so as to open up these coils more and more as the strip slides forward toward the large dispensing end of the frame. There the pawls 28 are engaged between the second and third endmost ties 11' and the strip is thereafter fed forward step by step by oscillation of handle 19, the latter working the disk 22 through about 60° in each full stroke, as limited by pin 30, the feed movement thus given strip 11 being just enough for the dispensing of one tie 11'. The tool is first placed in position over wire 13 where the vine 14 crosses, the wire and vine entering the open side 15 of the large end of frame 12. Then handles 18 and 19 are closed to feed the strip 11 forward and cause the dispensed endmost tie 11' to embrace and coil closely around the wire and vine, whereupon, at the end of the closing movement of the handles, the blade 17 cuts through web 16 severing the connection between the applied tie 11' and the strip 11. When closing pressure is relieved, the handles return to normal position under action of springs 32 and 33, and in this movement disk 22 is returned also to starting position, thereby engaging pawls 28 behind the next tie in the strip, and the tool is ready for the next operation.

It is believed the foregoing description conveys a good understanding of the objects and ad-

vantages of my invention. The appended claims have been drawn to cover all legitimate modifications and adaptations.

I claim:

1. A tying device adapted for applying vine tying material in the form of an elongated C-section strip of resilient flexible sheet material having an inherent tendency to curl up about an axis extending longitudinally relative to said strip, the C of such section in curled form being of a diameter internally that is more than large enough to accommodate a vine extended therethrough and being also adapted to accommodate in like manner a wire on which the vine is to be fastened, said strip having uniformly spaced parallel slots provided in opposite sides thereof, defining therebetween the body portions of a plurality of C-shaped tie portions that are adapted to be used as so many separate vine ties when they are cut from the strip, there being only narrow connecting web portions left by said slots between the middle portions of adjoining ties in the strip, which web portions are adapted to be cut through easily, said tying device comprising a generally conical frame over which said strip is adapted to be slipped endwise from the small end of the cone to spread open the curled up tie portions thereof, at least the large end of said frame being open on one side diametrically opposite where the web portions of the strip slipped over said frame are located and adapted to receive therein a portion of a vine and a supporting wire or other element therefor.

2. A tying device adapted for applying vine tying material in the form of an elongated C-section strip of resilient flexible sheet material having an inherent tendency to curl up about an axis extending longitudinally relative to said strip, said strip having uniformly spaced parallel slots provided in opposite sides thereof, defining therebetween the body portions of a plurality of C-shaped tie portions that are adapted to be used as so many separate vine ties when they are cut from the strip, there being only narrow connecting web portions left by said slots between the middle portions of adjoining ties in the strip, which web portions are adapted to be cut through easily, said tying device comprising a generally conical frame over which said strip is adapted to be slipped endwise from the small end of the cone to spread open the curled up tie portions thereof, at least the large end of said frame being open on one side diametrically opposite where the web portions of the strip slipped over said frame are located and adapted to receive therein a portion of a vine and a supporting wire or other element therefor, and manually operable cutting means on the large end of said conical frame for severing the connecting web between the endmost tie portion and the rest of the strip when said endmost tie portion is slipped past the large end of said conical frame.

3. A tying device adapted for applying vine tying material in the form of an elongated C-section strip of resilient flexible sheet material having an inherent tendency to curl up about an axis extending longitudinally relative to said strip, said strip having uniformly spaced parallel slots provided in opposite sides thereof, defining therebetween the body portions of a plurality of C-shaped tie portions that are adapted to be used as so many separate vine ties when they are cut from the strip, there being only narrow connecting web portions left by said slots between

the middle portions of adjoining ties in the strip, which web portions are adapted to be cut through easily, said tying device comprising a generally conical frame over which said strip is adapted to be slipped endwise from the small end of the cone to spread open the curled up tie portions thereof, at least the large end of said frame being open on one side diametrically opposite where the web portions of the strip slipped over said frame are located and adapted to receive therein a portion of a vine and a supporting wire or other element therefor, manually operable cutting means on the large end of said conical frame for severing the connecting web between the endmost tie portion and the rest of the strip when said endmost tie portion is slipped past the large end of said conical frame, and strip feeding means interconnected with said manually operable cutting means so that the strip is first fed forward and then the endmost tie portion projected beyond the large end of said conical frame is cut off.

4. A tying device adapted for applying vine tying material in the form of an elongated C-section strip of resilient flexible sheet material having an inherent tendency to curl up about an axis extending longitudinally relative to said strip, said strip having uniformly spaced parallel slots provided in opposite sides thereof, defining therebetween the body portions of a plurality of C-shaped tie portions that are adapted to be used as so many separate vine ties when they are cut from the strip, there being only narrow connecting web portions left by said slots between the middle portions of adjoining ties in the strip, which web portions are adapted to be cut through easily, said tying device comprising a generally conical frame over which said strip is adapted to be slipped endwise from the small end of the cone to spread open the curled up tie portions thereof, at least the large end of said frame being open on one side diametrically opposite where the web portions of the strip slipped over said frame are located and adapted to receive therein a portion of a vine and a supporting wire or other element therefor, a pair of handles adapted to be grasped in one hand, like the handles of a pair of shears, and pivotally mounted in assembled relation to the large end of said frame, cutting means operable by movement of one of said handles to sever the endmost tie portion from said strip when it has been projected beyond the large end of said frame, and step by step feed means operable in timed relation to said cutting means by movement of the other of said handles and arranged to feed the strip forward a step equivalent to the length of one tie portion before said cutting means is operated.

5. A tying device adapted for applying vine tying material in the form of an elongated C-section strip of resilient flexible sheet material having an inherent tendency to curl up about an axis extending longitudinally relative to said strip, said strip having uniformly spaced parallel slots provided in opposite sides thereof, defining therebetween the body portions of a plurality of C-shaped tie portions that are adapted to be used as so many separate vine ties when they are cut from the strip, there being only narrow connecting web portions left by said slots between the middle portions of adjoining ties in the strip, which web portions are adapted to be cut through easily, said tying device comprising a generally conical frame over which said strip is adapted to be slipped endwise from the small end of the cone

5 to spread open the curled up tie portions thereof, at least the large end of said frame being open on one side diametrically opposite where the web portions of the strip slipped over said frame are located and adapted to receive therein a portion of a vine and a supporting wire or other element therefor, and combined strip feed means and tie cut-off means manually operable in timed relationship to one another relative to the large end 10 of said frame, so that the strip is fed forward enough to project one tie portion from the end of said frame and then the tie portion so projected is severed from the strip.

6. A tying device as set forth in claim 2, wherein in said conical frame is formed from a piece of sheet metal, said piece having an extension on one edge portion thereof at the large end of the cone providing a support, said manually operable cutting means comprising a blade member pivoted on said support for oscillation in a plane crosswise relative to the large end of said frame.

7. A tying device as set forth in claim 3, wherein in said conical frame is formed from a piece of sheet metal, said piece having an extension on one edge portion thereof at the large end of the cone providing a support, said manually operable cutting means comprising a blade member pivoted on said support for oscillation in a plane crosswise relative to the large end of said frame, 25 said manually operable cutting means and strip feeding means both comprising handle members pivoted on said support for manual operation.

8. A vine tying device comprising an elongated frame member tapered in form and of C-shaped section from end to end, whereby it is adapted to straddle, at least at the large end, a vine and a wire or other support onto which the vine is to be tied, said frame member being adapted to support thereon a self-closing resilient tie of

40 C-shaped form slidable over the frame from the small end to and over the large end, whereby it is spread enough in passing over the large end of said member to embrace the vine and the wire or other element before closing again under an inherent tendency to contract to a smaller diameter.

9. A vine tying device comprising an elongated frame member tapered in form and of C-shaped section from end to end, whereby it is adapted to straddle, at least at the large end, a vine and a wire or other support onto which the vine is to be tied, said frame member being adapted to support thereon a strip of self-closing resilient ties of C-shaped form slidable over the frame from the small end to and over the large end, whereby they are spread enough to embrace the vine and the wire or other element before closing again under their inherent tendency to contract to a smaller diameter, and means for cutting the ties from the strip comprising a blade mounted for movement in shearing relation to the large end of the frame.

10. A device as set forth in claim 9 including means for feeding the strip endwise relative to the frame toward the large end.

11. A tying device of the character described, comprising an elongated frame member of gradually enlarged form toward one end and C-shaped in section at least at the large end, whereby it is adapted to straddle the article to be operated upon, said frame member being adapted to support thereon a strip of self-closing resilient ties of C-shaped form slidable on the frame member toward and over the large end, whereby the ties are spread enough to embrace

the aforesaid article before closing again under their inherent tendency to contract to a smaller diameter, and means for cutting the ties from the strip comprising a blade operated in shearing relation to the large end of the frame member.

12. A device as set forth in claim 11, including means for feeding the strip endwise relative to the frame toward the large end and in a predetermined timed relationship with the operation of said blade.

13. A tying device of the character described, comprising an elongated frame member of gradually enlarged form toward one end and C-shaped in section at least at the large end, whereby it is adapted to straddle the article to be operated upon, said frame member being adapted to support thereon a strip of self-closing resilient ties of C-shaped form slideable on the frame member toward and over the large end, whereby the ties are spread enough to embrace the aforesaid article before closing again under their inherent tendency to contract to a smaller diameter, a manually operable handle oscillatably mounted relative to the large end of said frame member and operating a blade in shearing relation to said end, and another manually operable handle normally disposed in acute angle relationship to and adjacent the first handle oscillatably mounted relative to the large end of said frame member and connected to operate means for feeding the strip endwise relative to the frame member toward the large end and in a predetermined timed relationship with the operation of said blade.

14. A device as set forth in claim 13, including a stop for limiting movement of the strip feeding means, a first spring means interconnecting said handles to resist closing of the handles and acting to return said handles to their normal acute angle relationship, and a second spring means acting between the first handle and the frame member tending to resist closing movement of the handles and acting to return the first handle to its starting position.

15. A device of the character described, comprising a generally conical tubular frame, the large end of which is open lengthwise on one side and is adapted for entry therein of a length of vine, such as a grape vine, and a supporting wire, leaving the small end of the cone in radially spaced relation to the wire to permit threading onto the small end a vine tying ringlet that is adapted to be spread open by movement endwise of said frame to receive the vine and wire when passed over the large end of said frame.

16. A device of the character described, comprising a generally conical tubular frame, the large end of which is open lengthwise on one side and is adapted for entry therein of a length of

vine, such as a grape vine, and supporting wire, leaving the small end of the cone in radially spaced relation to the wire to permit threading onto the small end a vine tying ringlet that is adapted to be spread open by movement endwise of said frame to receive the vine and wire when passed over the large end of said frame, and manually operable cutting means on the large end of said frame movable in shearing relation to the end surface.

17. A device of the character described, comprising a generally conical tubular frame, the large end of which is open lengthwise on one side and is adapted for entry therein of a length of vine, such as a grape vine, and a supporting wire, leaving the small end of the cone in radially spaced relation to the wire to permit threading onto the small end a vine tying ringlet that is adapted to be spread open by movement endwise of said frame to receive the vine and wire when passed over the large end of said frame, manually operable cutting means on the large end of said frame movable in shearing relation to the end surface, and feeding means interconnected with said cutting means to project the ringlet material beyond the large end of the frame to be cut off.
